UNITED STATES PATENT OFFICE.

HOMER P. SMITH, OF APPLETON, WISCONSIN, ASSIGNOR OF ONE-THIRD TO F. EDWARD SAECKER AND ONE-THIRD TO HERMAN G. SAECKER, BOTH OF APPLETON, WISCONSIN.

WIRE-CUTTING DEVICE.

1,309,664.

Specification of Letters Patent.

Patented July 15, 1919.

Original application filed February 5, 1918, Serial No. 215,500. Divided and this application filed June 21, 1918. Serial No. 241,166.

To all whom it may concern:

Be it known that I, HOMER P. SMITH, a citizen of the United States, and resident of Appleton, in the county of Outagamie and State of Wisconsin, have invented certain new and useful Improvements in Wire-Cutting Devices; and I do hereby declare that the following is a full, clear, and exact description thereof.

10 This invention relates to improvements in means for cutting wire into predetermined lengths, the same being particularly adapted for use in connection with machines for making hairpins as illustrated in my co-pending application Serial No. 215,500, filed February 5, 1918.

As pointed out in said application it is particularly desirable in hairpin forming machines, to cut the wire into predetermined lengths in such a manner that the ends of said lengths will be free from any irregularities or roughness which might tend to catch the user's hair. The provision of an improved means for accomplishing this is 25 the principal aim of the present invention.

With this general object in view the invention resides in certain peculiarities of construction, combination and arrangement of parts which will be hereinafter more particularly pointed out in the description and claims.

In the accompanying drawings:

Figure 1 is a sectional view through the table of the hairpin forming machine with the invention attached thereto.

Fig. 2 is a plan view of the cutting device with parts broken away and in section.

Fig. 3 is an elevational end view of the invention showing the same attached to the table of a hairpin forming machine.

Fig. 4 is an enlarged transverse sectional view through the cutting blade and adjacent members of the device, and

Fig. 5 is a view similar to Fig. 4 of a modified form in which the cutting member is carried by the movable gripping member.

Referring now more particularly to the accompanying drawings the numeral 1 designates a horizontally positioned table over which a wire W is fed and intermittently operated upon by the several hairpin forming mechanisms illustrated in the above referred to co-pending application. As previously stated great difficulty has been experi-

enced in retaining the ends or cut-off parts 55 of the wire smooth or without irregular places which might catch in the user's hair. In the present invention this is accomplished by the provision of a blade 2 having a substantially V-shaped cutting edge the faces of 60 which are concave. Thus if a wire is rolled over a stationary blade of this type, and at the same time forced against the same, or if a movable blade of such shape is forced against the rolling wire it will be severed 65 and the resulting ends will be substantially hemispherical or rounded as shown in Figs. 4 and 5.

The blade 2 may be either secured in the bottom of a transversely disposed channelled 70 member 3 positioned on the table 1 and the wire rolled thereover by means of a sliding gripping member 4 or the blade may be carried by the member 4 itself. This gripping member 4 is movable transversely of the 75 wire by the engagement of one end of an intermediately pivoted lever 5 therewith, said lever 5 in turn being actuated by a cam face formed on a cam plate or disk 6. This cam plate is rotatable with a main driven 80 shaft 7 positioned longitudinally of the table 1.

The end of the gripping member 4 which engages the wire is normally spaced above the bottom of the channelled member 3 by 85 means of a spring 8, one end of which engages an ear 9 formed on the gripping member and the other end contacts with the bifurcated end of a stem 10 pivoted to a relatively stationary guide member 11. The 90 end of the member 4 which engages the wire W is provided with a cam face 4' which, when said bar is moved toward the wire and the blade 2, engages with the end of the guide member 11 whereby said end of the 95 bar is moved toward the bottom of the channelled member 3.

Thus, longitudinal shifting of the movable gripping member 4 toward the wire W by means of the lever 5 will cause the wire to 100 be rolled toward and over the blade 2 and simultaneously with this movement said wire will be forcibly engaged and pressed against the latter and cut. It will be further seen, as best illustrated in Figs. 4 and 5, 105 that the height of the knife above the bottom of the channelled member 3 which forms a gripping member in conjunction with the

member 4 is less than the diameter of the wire thus allowing the wire positioned upon the opposite sides of the blade to be firmly gripped between the movable and stationary member while it is being rolled across the 5 knife and cut.

In order to permit vertical adjustment of the guide member 11 the same is pivoted in a channeled bracket 12 and is provided with 10 an extension 11' having threaded therein a set-bolt 13 provided with a lock-nut 13' which permits the extension 11' to be adjusted vertically thereby obtaining a corresponding adjustment upon the end engaging 15 the cam face 4'.

The wire is directed into the cutting mechanism by an inverted channel shaped guide 14, one flange of which has a laterally extending ear 15 whereby it may be pivoted to 20 the table 1. The opposite flange of the guide member is engaged by a leaf spring 16 by which it is forced against a stop 17. The wire W is fed to the cutting mechanism through the guide 14 so that the portion to 25 be severed will always be in correct position to permit effective operation of the mechanism. During the operation of the cutting device the wire W is rolled and the guide 14 shifted to compensate for this movement. 30 After the wire has been forced over the knife and a cut effected the end disposed in the guide member 14, which is to be fed to the cutting device, will be returned to its normal position by the spring 16 during the 35 inoperativeness of the cutting device.

From the foregoing description it will be readily seen that a simple economical cutting device has been constructed which is efficient in operation and while I have shown 40 and illustrated one method in which the invention might be carried out it will be readily appreciated that various minor changes and details of construction might be made by those skilled in the art without departing from the spirit of the invention. 45

What I claim as new is:

1. In a machine of the class described, a wire cutting device comprising a stationary blade, a movable gripping member having a cam face, a guide member adapted to engage the cam face of the movable gripping member to cause the same to engage the wire and roll it over the blade to effect a cutting, and means for urging the gripping member toward the guide member. 50

2. In a machine of the class described, a wire cutting device comprising a stationary

cutting blade, a movable gripping member having a cam face, a guide member adapted to engage the cam face of the movable gripping member, means for actuating said gripping member toward the guide member, and means for adjusting the guide member to regulate the tension of the movable member upon the wire. 60

3. In a machine of the class described, a wire cutting device comprising a stationary cutting blade, a movable gripping member having a cam face, a guide member adapted to engage the cam face of the movable gripping member, means for actuating said gripping member toward the guide member, means for adjusting the guide member to regulate the tension of the movable member upon the wire, and means for returning the 70 movable gripping member to its normal position. 75

4. In a machine of the class described, a wire cutting device comprising a cutting blade, wire gripping members adapted to 80 rotate the wire across said blade, and a yieldable wire guide adapted to guide the wire to the cutting device and yield upon the rolling movement of the wire.

5. A wire cutting device including opposed 85 members, a cutting blade on one of said members, means for moving one of said members with respect to the other to procure rolling movement of the wire with respect to the blade, a channeled wire guide reciprocal in the substantial direction of rolling 90 movement of the wire, and means yieldably urging said guide in one direction of movement whereby to direct wire in position for initial rolling engagement. 95

6. A wire cutting device including a base member, a guide spaced from the base member, a shiftable member movable between the guide and base member and having a cam portion engageable with the guide, a blade 100 carried by one of said members and engageable with wire between the members for rolling said wire against the other member and cutting it, an extension on the shiftable member, a spring coacting with the guide member and the extension for urging said shifting member outwardly and toward the guide member, and means for moving the shifting member inwardly to cut the wire. 105

In testimony that I claim the foregoing I have hereunto set my hand at Appleton, in the county of Outagamie and State of Wisconsin. 110

HOMER P. SMITH.
